CLAIM

The ornamental design for a charging dock for serum device, as shown and described.

DESCRIPTION

FIG. 1 is a top, front perspective view of the charging dock for serum device.

FIG. 2 is a front elevation view of the charging dock for serum device of FIG. 1.

FIG. 3 is a back elevation view thereof.

FIG. 4 is a right side elevation view thereof.

FIG. 5 is a left side elevation view thereof.

FIG. 6 is a top plan view thereof; and,

FIG. 7 is a bottom plan view thereof.

In the drawings, the equal-length broken lines in the drawings depict environmental subject matter that forms no part of the claimed design.

1 Claim, 4 Drawing Sheets
